UNITED STATES PATENT OFFICE.

HAROLD SMITHWICK, OF RUMFORD FALLS, MAINE.

BUNCHING AND COUNTING MACHINE.

No. 926,904.

Specification of Letters Patent.

Patented July 6, 1909.

Application filed October 5, 1908. Serial No. 456,315.

To all whom it may concern:

Be it known that I, HAROLD SMITHWICK, a citizen of the United States, and a resident of Rumford Falls, in the county of Oxford and State of Maine, have invented certain new and useful Improvements in Bunching and Counting Machines, of which the following is a specification.

This invention relates to bunching and counting machines and has for its object to provide means for gathering into bunches, each containing a predetermined number, sheets of paper, metal or other material, cards, envelops, paper bags and other articles.

The product of many modern automatic machines is delivered therefrom at high speed and at a uniform rate and means for gathering said product into bunches, each containing a predetermined quantity, is a highly desirable adjunct to such machines.

The present invention has for its object to provide means which while receiving the articles from such automatic machines at high speed will with great accuracy gather and arrange them into bunches each containing a predetermined number.

To that end my improved machine comprises parts and mechanisms as illustrated, in its preferred embodiment, in the accompanying drawings, wherein—

Figure 1 is a side elevation thereof and Fig. 2 is a front elevation corresponding with the side elevation of Fig. 1.

My improved machine comprises one or more receptacles or gathering boxes, in the illustrations two are shown, 2 and 3 respectively, preferably having three sides only, as bottom 4, end 5 and side 6 of box 3. Each of said boxes has its bottom as 4 of box 3, inclined downwardly from the open receiving end toward rear end as 5 to facilitate the reception and retention of articles delivered thereto. Box 2 has thereover bridge 7 preferably substantially covering said box and inclined downwardly toward box 3. The object of this bridge is to deflect into box 3, any article delivered onto said bridge. It is therefore obvious that said bridge 7 may vary materially from the form and size shown without detracting from its described usefulness.

8, 9 are a pair of rolls suitably supported for rotative coaction for feeding articles, as 10, from some constant source of supply, not shown, toward boxes 2, 3 and in the line of the length of said boxes. Located between

said rolls 8, 9 and the receiving end of bridge 7 is a deflector or gate 11 pivotally supported at 12 to be swung upward and downward to guide thereover the articles delivered by rolls 8, 9 either onto or under bridge 7. When the articles are delivered onto said bridge they will pass into box 3, when they are delivered under said bridge they will pass into box 2. It is therefore obvious that gate 11 must be moved from its upper position to its lower position and vice versa, between the times of delivery of two consecutive articles by rolls 8, 9 and that in serving certain classes of high speed machinery the time allowed for the operation of said gate 11 is very brief. It is therefore necessary that the raising and lowering of said gate be not only accurately timed but done quickly. I will now describe the means which I have provided for raising and lowering said gate 11.

On that end of pivot shaft 12 toward supporting column 20 and to which shaft gate 11 is fixed is fixed arm 13 having formed on the outer end thereof pawl 14. Pivoted at the pawl end of arm 13 is roll 130. Mounted for rotation in the plane of roll 130, and supported from column 20 is disk 15. About one half of the periphery of said disk is of greater radius than the other half and when roll 130 rides on lower portion 151 of said periphery (see Fig. 1) gate 11 deflects the articles into box 2 but when roll 130 rides on higher portion 150 of said periphery gate 11 deflects the articles onto bridge 7 and thus into box 3. In most cases gate 11 may be actuated from its upper position to its lower position with sufficient speed by gravity or a convenient spring, not shown, may be used to assist said movement. For liberating said gate at the predetermined time I have provided a latch 16 attached to disk 15 contiguous circumferentially to the point of change from high to low on the periphery of said disk, and having a lip 17 in the plane of pawl 14 for coaction therewith. Said latch is so located that as it travels around on disk 15 in the direction of the arrow thereon pawl 14 drops off lip 17 just after an article has passed over gate 11 onto bridge 7 and said gate 11 reaches its lower position before the next article has passed sufficiently far onto said gate to engage said bridge. Said second article therefore passes under said bridge and into box 2.

For moving gate 11 from its lower to its

upper position I provide lifter arm 25 pivoted at 26 to the side of disk 15. Said arm 25 has a foot 27 projecting into a cavity 28 in disk 15. The face of said foot, when in said cavity 28, forms a portion of the periphery of said cam being a continuation of the low part 151 of said periphery at the end of said low part 151. The object of said foot 27 is to engage and lift roll 130 at the proper time to lift gate 11 from its lower to its upper position. Arm 25 and foot 27 are actuated to this end by the following means. Fixed to disk 15 is socket 17 having slidably mounted therein spring actuated plunger 18 for coaction with the free end of arm 25. Arm 25 has a rearwardly extending portion 250 having pin 19 therein for engagement with slot 21 in disk 15 for limiting the motion of said arm 25. Fixed to portion 250 of arm 25 and offset therefrom is pawl 22 for engagement with cam 23 supported on arm 24 outreaching from column 20. As disk 15 revolves in the direction of its arrow, pawl 22 rides up over cam 23 and swings arm 25 inwardly toward axis 40 of disk 15, presses inwardly spring actuated plunger 18 and carries foot 27 to its seat in lower portion 151 of the periphery of disk 15. After said foot 27 has passed under roll 130 of arm 13 pawl 22 drops off end 230 of cam 23, plunger 18 forces arm 25 carrying foot 27, and roll 130 on arm 13, upwardly, thereby suddenly moving gate 11 from its lower to its upper position.

Rolls 8, 9 may be geared together in the customary way not shown and may be driven in time with any machine in connection with which my improved machine is operated. Said rolls may be supported in bracket 30 fixed to column 20 and said bracket may also support pivot shaft 12 of gate 11 as shown.

For actuating disk 15 in proper time the following means are provided. Sprocket 29 on the shaft of lower feed roll 9 drives, by means of chain 31, sprocket 32 on shaft 33 in bracket 34 supported from column 20. On said shaft 33 is bevel gear 35 meshing with bevel gear 36 on shaft 37 having worm 38 fixed thereto. Said worm meshes with and drives worm gear 39 on shaft 40 of disk 15.

Boxes 2, 3 may be adjustably supported on arm 41 outstanding from column 20 and bridge 7 may also be supported on said arm 41.

I claim:

1. The combination of two boxes, a fixed bridge over one box for deflecting articles delivered thereon into the other box, means for delivering articles in a constant direction toward said bridge and means located below the path of travel of the articles and between said delivery means and said bridge shiftable for directing said articles thereover onto said bridge or under said bridge as desired.

2. The combination of two boxes arranged in sequence, a bridge over one box for deflecting articles delivered thereon into the other box, means for delivering articles in a constant direction toward said bridge and boxes, a gate located below the path of travel of the articles and between said delivery means and said bridge and means for moving said gate for directing said articles thereover onto said bridge or under said bridge as desired.

3. The combination of two boxes, a bridge over one box for deflecting articles delivered thereon into the other box, means for delivering articles in a constant direction toward said bridge, a gate located below the path of travel of the articles and between said delivery means and said bridge and automatic means for moving said gate at predetermined times for directing said articles thereover at one time onto said bridge and at another time under said bridge.

4. The combination of two boxes arranged in sequence, a bridge over one box for deflecting articles delivered thereon into the other box, means for delivering articles in a constant direction toward said bridge, a gate located below the path of travel of the articles and between said delivery means and said bridge, means for moving said gate for directing the articles thereover at one time onto said bridge and at another time under said bridge, and means controlled by the delivery means for moving the gate.

5. The combination of two boxes, a bridge over one box for deflecting articles delivered thereon into the other box, means for delivering articles in a constant direction toward said bridge, a pivotally supported gate located at one side of the path of travel of the articles and between said delivery means and said bridge and means for swinging said gate on its pivot for directing said articles always over one face of said gate at one time onto said bridge and at another time under said bridge.

6. The combination of means for feeding articles in a constant direction, a receiving box located adjacent to said feeding means and adapted to receive articles therefrom, a second box adjacent to said first box, a fixed bridge for directing articles delivered thereon into said second box, a gate located at one side of the path of travel of the articles and between said feeding means and said bridge, means for shifting said gate for directing the articles always over one face of said gate at one time onto said bridge and into the second box and at another time under said bridge into the first box.

7. The combination of two boxes, a bridge over one box for deflecting articles delivered thereto into the other box, means for delivering articles in a constant direction toward said bridge, a pivotally mounted gate

- between said delivery means and said bridge, means for swinging said gate upwardly on its pivot comprising a revolute cam having a portion of its periphery movably mounted therein, spring actuated means for moving said movable periphery portion and cam actuated means for first holding in its retracted position and at a predetermined time liberating to the action of the spring actuated means said movable periphery portion and means for revolving the revolute cam.
8. The combination of a receptacle, a fixed bridge thereover, means for delivering articles in a constant direction toward said bridge, means located at one side of the path of travel of the articles and between said delivery means and said bridge shiftable for directing said articles always over one face of said shiftable means, onto said bridge, or under said bridge as desired.
9. The combination of a receptacle, a bridge thereover, means for delivering articles in a constant direction toward said bridge, a gate located below the path of travel of the articles and between said delivery means and said bridge and means for moving said gate for directing said articles thereover onto said bridge or under said bridge as desired.
10. The combination of a receptacle, a bridge thereover, means for delivering articles in a constant direction toward said bridge, a gate located below the path of travel of the articles and between said delivery means and said bridge and means for moving said gate at predetermined times for directing said articles thereover at one time onto said bridge and at another time under said bridge.
11. In a device of the class specified the combination of a gate, a revolving cam, means for operating the gate from the cam, said cam having a low portion of its periphery bounded on each side by high portions, a movable foot normally forming that part of the low portion of said periphery adjacent to an oncoming high portion thereof and means for moving said foot outwardly when the gate operating means is in engagement therewith, from conformity with the low portion to conformity with said high portion of said periphery.
12. In a device of the class specified the combination of a gate, an arm fixed thereto, a revolving cam having its periphery in engagement with the free end of said arm; said cam having a portion of its periphery of less radius than those portions at each side thereof, a movable foot normally forming a part of said low portion of said periphery and adjacent to the oncoming higher portion thereof, means for moving said foot outwardly at predetermined times from conformity with the low part to conformity with the high part of said periphery for moving said arm to operate the gate.
13. In a device of the class specified the combination of a gate, a revolving cam, means for actuating the gate from the cam, said cam having a high portion and a low portion, each concentric with the axis of said cam, a movable foot normally forming a part of the low portion of said cam adjacent to the oncoming high portion thereof, and means for moving said foot outwardly at predetermined times into conformity with the high portion of said cam.
14. The combination of a gate, a revolving cam, means for actuating the gate from the cam, said cam having a high portion and a low portion, a movable foot normally forming a part of the low portion of said cam adjacent to the oncoming high portion thereof, means for moving said foot outwardly into conformity with the adjacent high portion of said cam when the gate actuating means is in engagement with said foot.
- Signed this 28 day of Sept., 1908, at Rumford Falls, Maine, before two subscribing witnesses.
